UNITED STATES PATENT OFFICE.

FREDERICK G. WACKER, OF CHICAGO, ILLINOIS, ASSIGNOR TO DETROIT RANGE
BOILER & STEEL BARREL COMPANY, OF DETROIT, MICHIGAN, A CORPORA-
TION OF MAINE.

METHOD OF MAKING HOOPED METALLIC RECEPTACLES.

1,419,705.

Specification of Letters Patent. Patented June 13, 1922.

Original application filed July 26, 1916, Serial No. 111,356. Patent No. 1,314,445, dated August 26, 1919.
Divided and this application filed July 26, 1919. Serial No. 313,448.

To all whom it may concern:

Be it known that I, FREDERICK G. WACKER, a citizen of the United States, and resident of Chicago, in the county of Cook and State 5 of Illinois, have invented certain new and useful Improvements in Methods of Making Hooped Metallic Receptacles, of which the following is a specification.

My invention relates to metallic receptacles such as barrels, casks, drums and the like, and the object thereof is to provide a novel and advantageous method of applying the so-called "rolling hoop" to the sheet-metal body of the receptacle, thereby producing an improved and stronger construction in a most efficient and economical manner. In my Patent No. 1,314,445 granted 15 August 26, 1919, of which this application is a division, I show and claim structure 20 such as may advantageously be made by my method.

In a general way, I proceed by slipping over the sheet metal body a suitable rolling hoop, and expanding the body-metal beyond 25 its normal position and into close contact with the hoop-interior along circumferential lines. For what I regard as most advantageous practice, in detail, I form outstanding beads closely flanking the hoop and also 30 expand the body beyond its normal diameter throughout the whole of the intervening hoop-underlying area, so that the body-metal, stretched more than the hoop—or without any stretching of the hoop—makes firm contact with the overlying interior face of the 35 hoop and so that, additionally, the flanking beads make pressure-contact with the hoop-edges. In my preferred construction I employ as a hoop a sheet-metal band pre- 40 formed to present an outwardly convexed rib or center-bead flanked by cylindrical flanges, and under these conditions I effect the displacement of the central belt of the outwardly-rolled body-metal so that it is 45 stretched into the concave of the hoop-rib, bringing the body-metal into close contact with the edges of the rib space (i. e., the inner edges of the hoop flanges). This also furthers the effectuation of pressure contact 50 of the flanking beads with the border-edges of the hoop. And further, under the stated conditions, I prefer to displace portions of

the hoop flanges together and jointly with the underlying body metal, to form locally-outwardly-bulged zones of contacting body- 55 and-hoop portions. The flanking beads and the outward expansion of the central zone into a hoop-rib and joint displacement of zones of the body and hoop are desirable features of my invention but are not es- 60 sential to its broadest aspects.

In the drawings, Fig. 1 is a side elevation of a barrel or drum showing the rolling hoops applied; Fig. 2 is a sectional view showing a fragment of the body and a preferred form of rolling hoop in the first stage of assemblage; Fig. 3 illustrates a rolling operation, and Fig. 4 shows a rolling operation on a different form of hoop.

The body 1 is initially in true cylindrical 70 form, in the preferred construction in the making of which I employ my method. Each rolling hoop may preferably be a sheet-metal ring or band preformed in any suitable way to provide a substantially central 75 rib or rolling-bead portion 2^a outwardly convexed and lying between two cylindrical flanges 2^b. As shown in Fig. 2, each such loop is loosely slipped on the cylindrical body to a proper horizontal position, that 80 is to say, in the practice of the invention the hoops are of slightly larger diameter than the external diameter of the body of the barrel and do not have to be driven on or shrunk on for self-retention, but on the contrary, a material initial looseness of the ring 85 on the cylinder for easy assemblage may be provided for without disadvantage. After the hoop is in proper horizontal position with relation to the body of the barrel, the body- 90 material is rolled outwardly at two points or lines to form the outwardly-extending beads 1^a at the outer edges of the flanges 2^b. At the same time, or as the result of a separate or subsequent rolling operation, the included hooped section, i. e., that portion of the body of the barrel located between these beads 1^a—is rolled outwardly as shown in Fig. 3, thereby forming a seat for the hoop, which seat is tightly forced against the hoop 100 flanges 2^b. Further, where the hoop is of the preferred centrally-ribbed construction shown in Fig. 2, the central part or zone of the distended portion or hooped-section of

the barrel body is expanded outwardly and into the rib or bead portion 2^a of the hoop, as shown at 1^b in Fig. 3.

In the formation of the beads 1^a and the expanding of the intervening section of the barrel body, such latter section is displaced outwardly so as to be out of line or in another plane with respect to the rest of the barrel body. This swelling or expansion 5 of the body into seating contact with an initially-larger hoop is important as an effective, certain and economical mode of securing the requisite hoop-seating and further the tendency to draw in the sides of the 10 beads 1^a insures the bringing of said beads into firm, pressure-exerting contact with the hoop edges. The body material is thus inevitably stretched much more than is the metal of the hoop, with the result that the 15 associated parts are kept in close, tight relationship and the distension of the body into the hoop-bead 2^a includes the flanges 2^b in contact under pressure with the body metal along both edges of the flanges. I prefer, 20 furthermore, when using a sheet-metal hoop, to stretch the hooped-section of the barrel body to such extent that it carries with it the inner portions of the hoop-flanges and this joint displacement of registering zones of 25 both the barrel body and the hoop (namely the zones within the width of flanges 2^b) outwardly, each beyond its initial circumferential position, as shown in Fig. 3 ensures 30 firm, even, extensive seating of the hoop on the body. Moreover, this expanding of the 35 barrel body makes a truss or locally bulged construction as shown, which is a very practical and efficient strengthener, as the weight of the barrel in rolling is borne by these 40 rolling hoops and any tendency of flattening of the truss is effectually resisted by the construction thus provided.

In Fig. 4 I have illustrated the application 45 of my invention to produce a modified form of construction wherein the rolling hoop, numbered 3, is of I-beam construction. In this form of metallic receptacle the same beads 1^a are formed in the barrel body and such body is outwardly extended at 1° beyond 50 its normal circumferential position to bear tightly against the base of the I-beam, it being understood that such hoop fits the barrel body loosely before the body is expanded, just as does the hoop 2 already described.

55 What I claim is:

1. The method of forming a metallic barrel and rolling hoop thereon which consists in applying to the exterior of the barrel a 60 loosely fitting hoop having an outwardly directed circumferential bead, expanding the body to form circumferential beads at the edges of the hoop, and also expanding the barrel body into the said hoop bead.

65 2. The method of forming a metallic bar-

rel and rolling hoop thereon which consists in applying to the exterior of the barrel a loosely fitting hoop having an outwardly directed circumferential bead, expanding the body to form circumferential beads at the 70 edges of the hoop, and also expanding the body intermediate said beads against the inner face of the hoop, and also expanding the barrel body in said hoop bead.

3. The method of forming a metallic barrel and rolling hoop thereon which consists in applying to the exterior of the barrel a loosely fitting hoop having an outwardly directed circumferential bead, expanding the body to form circumferential beads at 80 the edges of the hoop and also expanding the body intermediate said beads against the inner face of the hoop, and also stretching the metal of the barrel body and expanding it into the hoop bead so as to exert tension 85 thereagainst.

4. The method of forming a metallic barrel and rolling hoop thereon which consists in applying to the barrel a loosely fitting hoop, expanding the body to form circumferential beads at the edges of the hoop, and outwardly displacing the body portion that underlies the hoop beyond its initial circumferential position, stretching it in excess of 90 any stretching of the hoop and thereby putting the body into firm contact with the 95 hoop.

5. The method of forming a metallic barrel and rolling hoop thereon which consists in applying to the barrel a loosely fitting 100 hoop and forming in said body beads engaging and paralleling the hoop edges and outwardly displacing the section intermediate said beads beyond its initial circumferential position, stretching it in excess of any 105 stretching of the hoop and thereby putting the beads into pressure-exerting contact with the hoop edges.

6. The method of making a metallic barrel and rolling hoop which consists in placing 110 on the barrel body a loosely fitting sheet metal hoop, forming outwardly directed beads on the body engaging and paralleling said hoop, and outwardly bulging the section of the body intermediate said hoop together 115 with contacting parts of the sheet metal hoop, thereby putting the beads into pressure-exerting contact with edges of the hoop.

7. The method of making a cylindrical barrel and rolling hoop which consists 120 in placing on the cylindrical body a sheet metal hoop member having cylindrical side flanges and an intervening outwardly directed bead, outwardly expanding the section of the body that underlies the 125 flanged portions of the bead, and further expanding and forcing a central portion of the expanded part of the body into the hoop bead.

8. The method of making a cylindrical 130

- barrel and rolling hoop which consists in placing on the cylindrical body a sheet metal hoop member having cylindrical side flanges and an intervening outwardly directed bead, expanding the body of the barrel flanking the hoop flanges to form beads engaging and paralleling the said hoop flanges and outwardly expanding the intervening section of the body and the flanged portions of the bead, forcing a central portion of the expanded part of the body into the hoop bead and locally bulging the zones of body and hoop which intervene between the hoop-bead and the edge-beads of the body.
- 15 9. The method of hooping a sheet metal barrel which consists in loosely applying the cold hoop, and beading the barrel-body on both sides of the hoop and stretching the intermediate section of the barrel sufficiently 20 to bring zones thereof into seating contact with the loosely overlying hoop and to establish pressure-contact between the body-beads and the hoop-edges.
10. The method of forming a metallic 25 barrel and rolling hoop thereon which consists in applying to the exterior of the barrel a loosely fitting hoop having an outwardly directed circumferential bead, and expanding circumferential portions of the body of the barrel outwardly out of the plane of such body and against the hoop to form a hoop-bead-engaging distension and a hoop-edge-engaging bead.
11. The method of forming a metallic barrel and rolling hoop thereon which consists in applying to the exterior of the barrel a loosely fitting hoop having an outwardly directed circumferential bead, and forming hoop-edge flanking beads on the body and expanding the body of the barrel 30 into said hoop bead and displacing the same at such point outwardly out of the plane of the remainder of the body.
12. The method of making a barrel with a rolling hoop which consists in placing 35 on the body a sheet metal hoop having side flanges and an intervening outwardly-directed bead and outwardly expanding that portion of the body-metal which underlies the flanges of the hoop beyond 40 its initial circumferential position, stretching it in excess of any stretching of the hoop-flanges and expanding a portion of the body into the hoop-bead and thereby putting the body-material in firm contact with said 45 50 55 hoop-flanges.

FREDERICK G. WACKER.
